UNITED STATES PATENT OFFICE.

ARCHIBALD JONES, OF PITTSBURGH, PENNSYLVANIA.

VERTICAL RETORT ZINC-SMELTING FURNACE.

1,424,825.

Specification of Letters Patent. Patented Aug. 8, 1922.

Application filed February 19, 1921. Serial No. 446,415.

To all whom it may concern:

Be it known that I, ARCHIBALD JONES, a citizen of the United States, and resident of Pittsburgh, in the county of Allegheny and State of Pennsylvania, have invented certain new and useful Improvements in Vertical Retort Zinc-Smelting Furnaces, of which the following is a specification.

This invention relates to smelting furnaces, and more particularly to zinc smelting furnaces, and has for one of its objects the provision of a smelting furnace having a plurality of rows of vertical retorts.

Another object is to provide a smelting furnace having a single fixed condenser built into the furnace body and adapted to serve a plurality of retorts, thereby providing a condenser that will keep the zinc hot and also will be of sufficient length to condense practically all of the zinc fumes.

Another object is to provide a zinc smelting furnace having retorts that may be cleaned and charged without the necessity of removing the condensers, as has been the practice in zinc smelting furnaces heretofore.

Another object is to provide a furnace having condensers that are particularly adapted for the use of filters in connection therewith, since such condensers are fixed in position, and there are a lesser number of condensers than heretofore.

A further object is to provide an improved mechanism for charging and cleaning out the retorts.

These and other objects and advantages will be more fully brought out in the following specification and illustrated in the accompanying drawings, in which:—

Figure 1 is a side elevation of a smelting furnace constructed in accordance with my invention, and having a portion of the side wall removed to show the interior construction.

Figure 2 is a top plan of the smelting furnace partly in section, the section being taken on the line II—II of Figure 1.

Figure 3 is a sectional end elevation on the line III—III of Figure 2.

Referring particularly to the drawings, the smelting furnace illustrated therein has side walls 2, and top and bottom walls 3 and 4 respectively. The furnace is provided at one end with stacks 5 and 5', which are adapted to carry off the products of com-

bustion, while the opposite end converges, forming a constricted or narrow fuel passage 6, opening into the body of the furnace.

The furnace chamber is divided in two sections by a longitudinally extending wall 7 which also serves as a center support for the top wall 3.

The top wall 3 is provided with a plurality of substantially rectangular depressions or recesses 8 arranged in transverse rows across the furnace, two of such recesses being shown on each side of the wall 7, in the construction of the drawings. The recesses or depressions 8 are adapted to be closed by removable covers 9, and have their lower walls apertured for the reception of the upper end of the vertical retorts 10.

The bottom wall 4 of the furnace is provided with transverse rows of apertures 11 in line with the apertures in the opening through the bottom wall of the recesses 8. The apertures 11 flare outwardly from their center toward both ends, and the lower ends of the retorts 10 are fitted therein so that their lower ends are supported on the side walls of the apertures 11 above their center.

A fixed condenser or condensing chamber 13 is built into the top wall 3 between each two rows of the recesses or depressions 8 and extends from the wall 7 outwardly and opens through the side walls 2. The condensers 13 are built integral with the top wall 3 and extend below the plane of the bottom of the top wall into the furnace chamber and are inclined downwardly toward their outer ends so that the zinc condensed therein will run by gravity to then be discharged through the open end thereof.

Suitable ports or passages 15 are formed between the recesses or depressions 8 and the abutting condenser 13 so that one condenser serves two rows of recesses 8 and the retorts 10 which open into the recesses. As shown in the drawings, each condenser 13 serves eight retorts.

The condensers may be provided with a suitable lining 16 semi-circular in cross section, if desired, to form a suitable surface over which the condensed metallic zinc will run.

The retorts 10 are sealed against communication with the furnace chamber at their upper ends with clay or similar material as at 17, and at their lower ends with

clay, sand or other similar material as at 18, to prevent air or other gases from the furnace chamber entering the retorts.

The lower ends of the retorts 10 are closed by removable cone-shaped plugs 19 composed of a metal base 20 and a clay top 21. The plugs 19 are each supported and operated by a suitable lever mechanism, hung from the bottom wall 4 of the furnace which 10 comprises a lever 22 pivotally hung, by one end, from a suitable beam secured to the bottom wall of the furnace, a plug lever 23 of considerably shorter length than the lever 22, which is pivotally secured by one end to the 15 center of the metal base 20 of the plug 19, and a counterweight lever 24 having one end pivotally connected to the plug lever 23, and pivotally secured intermediate its ends to the lever 22. A suitable weight 25 is secured to the other or free end of the lever 24 and normally serves to hold the plug 19 seated within the retort 10.

The plugs 19 are of such size that they extend into the retorts sufficiently so that their 25 upper faces will be in substantially the same plane as the bottom of the furnace chamber, in this way forming a bottom for the retorts that is in the same plane as the bottom of the furnace chamber, and thereby keeping 30 the charge within the retorts above the furnace bottom so that it will all be heated sufficiently to remove the entire zinc content.

The plugs 19 are opened or lowered by 35 means of chains 27 having one end secured to the lower or free end of the counterweight levers 24 and the other end to a shaft 28 suitably journaled on the underside of the furnace and provided with a ratchet and 40 pawl mechanism 29 and with a squared head 30 which is adapted to be engaged by a suitable tool for turning. Each of the shafts 28 serves all of the plugs for the retorts paralleling one side of each condenser, and 45 as the shaft is rotated the respective chains 27 will be wrapped on the shaft, thereby lifting the levers 24 and weights 25, rocking the levers 24 on the levers 22, and pulling down the levers 23 and plugs 19 for all the retorts 50 in the row served by the shaft.

Removable condensers 31 are adapted to be telescopically engaged within the outer end of the fixed condensers 13 to condense any of the zinc gases or fumes not condensed within the condensers 13.

Air for supporting combustion within the furnace chamber is supplied by suitable air mains 32 on each side of the furnace chamber and having branches 33 entering the 60 chamber.

An overhead charging crane 35 is mounted to move longitudinally of the furnace on a track 34 and is provided with suitable bins 36 for holding the ores to be smelted. A 65 plurality of charging buckets 37 are pivot-

ally mounted on the bottom of the bins 36 and are held in raised position by a latch 38 adapted to be controlled from the crane operator's cab 39. Suitable shutters 40 are connected to the buckets 37 and are adapted to close the spouts from the bin 36 as the buckets 37 are dumped to charge their load.

A crane buggy 41, mounted on the tracks 42 on crane 35 to move transversely of the furnace, carries a suitable tool 43 for pushing out the residue from the retorts 10 if it should stick. The tool 43 also is provided with hooks 44 for lifting the closures 9 over the recesses or depressions 8.

Suitable tools may be substituted for the 80 tool 43 if desired for removing and replacing the retorts 10 when they are broken.

In case the charge of ores is too fine and dense for the free escape of gases from the retort, it should be briquetted, the briquettes 85 broken and the broken briquettes charged. Smelting begins at the walls of the retort and works toward the center and therefore a porous core will remain in the retort until all of the zinc has been extracted.

90 Filters may be attached to the removable condensers 31 for removing any solid matter from the gases since there are a lesser number of condensers than heretofore used and also the condensers are not taken down for 95 charging and cleaning out the retorts. Heretofore the use of filters has been considered impractical since they had to be taken down daily to permit of the removal of the condensers in order to clean out and 100 charge the retorts.

It will be apparent that this form of zinc smelter will have many advantages over the usual retort smelter. The labor necessary for scraping out and filling the usual retorts 105 is eliminated, the condenser being built into the furnace will keep the zinc fume hot so that it will condense as liquid zinc instead of blue powder, the necessity of removing the condensers in cleaning and charging the 110 retorts is eliminated, the condensers are of sufficient length to condense all of the zinc fumes, and the number of condensers is greatly reduced since one condenser serves eight retorts where heretofore the practice 115 has been to have a separate condenser for each retort.

Other advantages of the invention will be apparent to those skilled in the art to which this invention appertains, and as it is susceptible of a number of modifications without departing from the spirit of the invention, no limitations, other than those expressly included in the appended claims are to be imposed.

125 I claim:

1. A smelting furnace comprising a furnace chamber, a plurality of vertical retorts arranged in rows in said chamber, and a fixed condenser arranged between two rows 130

of said vertical retorts and communicating with each of said retorts in said rows.

2. A zinc smelter comprising a furnace chamber, a plurality of vertical retorts arranged in said chamber, said retorts being sealed from communication with said chamber, and a single fixed condenser built within said furnace chamber and adapted to serve a plurality of said retorts.

10 3. A zinc smelting furnace comprising a furnace chamber having its top and bottom walls apertured for the reception of a plurality of vertical retorts, said retorts being sealed from communication with said furnace chamber, and a plurality of fixed condensers built into said furnace chamber, each of said condensers being arranged to receive the zinc gases from a plurality of said retorts.

15 4. A zinc smelting furnace comprising a furnace chamber having its top and bottom walls apertured for the reception of a plurality of vertical retorts, said retorts being arranged in rows and sealed against communication with said furnace chamber, a plurality of fixed condensers built into said furnace chamber, one of said condensers being arranged between each two rows of said retorts and communicating with the retorts of said rows to receive the zinc gases therefrom, and means for closing the ends of said retorts.

20 5. A zinc smelting furnace comprising a

furnace chamber having its top and bottom walls apertured for the reception of a plurality of vertical retorts, said retorts being arranged in rows and sealed against communication with said furnace chamber, a plurality of fixed condensers built into said furnace chamber, one of said condensers being arranged between each two rows of said retorts and communicating with the retorts of said rows to receive the zinc gases therefrom, and removable plug closures for the lower ends of said retorts, said plugs being of such size that they extend into said retorts to approximately the bottom of the furnace.

25 6. A zinc smelting furnace comprising a furnace chamber having its top and bottom walls apertured for the reception of a plurality of vertical retorts, said retorts being arranged in rows and sealed against communication with said furnace chamber, a plurality of fixed condensers built into said furnace chamber, one of said condensers being arranged between each two rows of said retorts and communicating with the retorts of said rows to receive the zinc gases therefrom, and a removable condenser telescopically engaged within said fixed condensers, and means for closing the ends of said retorts.

In testimony whereof I have hereunto signed my name.

ARCHIBALD JONES.
